Abraham J. Freedenberg,
By Frederick V. Winters,
Attorney

UNITED STATES PATENT OFFICE.

ABRAHAM J. FREEDENBERG, OF NEW YORK, N. Y.

ABDOMINAL SUPPORTER.

Application filed October 22, 1921. Serial No. 509,513.

To all whom it may concern:

Be it known that I, ABRAHAM J. FREEDENBERG, a citizen of the United States, residing at New York, in the county and State of New York, have invented certain new and useful Improvements in Abdominal Supporters, of which the following is a full, clear, and exact specification.

This invention relates to abdominal supporters and has for its object to provide an improved device of this kind which will fit and retain its position better than prior constructions.

The invention contemplates the provision of a rigid shield to fit the abdomen of the wearer, and a supporting belt attached to said shield in such a way as to insure the holding thereof in correct position regardless of different movements of the body, thereby insuring comfort to the wearer and eliminating the inconvenience caused by constant shifting of prior forms of supporters. Other objects will appear as the description proceeds.

The invention will be first hereinafter described in connection with the accompanying drawings which constitute part of this specification, and then more specifically defined in the claims at the end of the description.

In the accompanying drawings wherein similar reference characters are used to designate corresponding parts throughout the several views:

Figure 1 is a perspective view of a supporter made substantially in accordance with this invention.

Figure 2 is a side view of the supporter showing its position when in use, and

Figure 3 is a central vertical section through the shield.

The shield 1 is preferably made of light but rigid metal covered on the inside with a leather lining 2. Said shield has an upper

channeled portion 3 to fit the front of the abdomen and a lower channeled portion 4 arranged at an inwardly extending angle to the upper portion 3 for fitting and supporting the lower part of the abdomen. As clearly shown in Figures 2 and 3, said upper and lower portions 3 and 4 of the shield

form a pocket which may be varied in contour to fit the abdomen of the wearer. The edge of the lower portion 4 is reinforced with a wire bead 5 for retaining it in correct position, said bead extending upward slightly beyond the juncture 6 between the lower portion and upper portion 3 of the shield, as indicated at 7 in Figure 2.

The shield is preferably made from a casting taken of the parts it is intended to fit so that when applied there will be little difficulty in retaining it in position. The bead 5 prevents the inwardly extending lower portion 4 of the shield from sagging or warping out of correct position.

The shield 1 is held in place by a flexible belt 8 having diverging straps 9 and 10 at its extremities. The upper strap 9 is passed through a metal loop 11 secured to the upper portion 3 of the shield 1, while the lower strap 10 extends below a metal hook 12 on the lower portion 4 of said shield, so that when the straps are secured as shown in Figure 2, the upper one has a tendency to retain the shield against upward movement, while the lower strap holds the inwardly bent lower portion of the shield in contact with the lower part of the abdomen and prevents downward movement of said shield.

Experiment has shown that when the shield is made as herein shown and described and it is secured in place by the arrangement of straps illustrated, the wearer may twist and turn his body without danger of displacing the supporter.

I claim:

An abdominal shield and supporter comprising a rigid plate formed to accurately fit the contour of the wearer's abdomen, said plate having an upper shield portion, and a lower portion to extend under the abdomen for supporting the same as on a shelf, and means for securing the plate in position on the wearer including a downwardly pointing hook on said lower shelf-like portion of the plate, and a strap extending from above and engaging said hook.

In testimony whereof I have signed my name to this specification.

ABRAHAM J. FREEDENBERG.
